Primary Examiner — Kendra Leslie Hamilton

Assistant Examiner — Elizabeth S Struble

(57) **CLAIM**

The ornamental design for a massage gun, as shown and described.

DESCRIPTION

FIG. 1 is a front elevational view of a massage gun showing my new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a rear elevational view thereof;

FIG. 7 is a perspective view thereof;

FIG. 8 is another perspective view thereof;

FIG. 9 is another perspective view thereof;

FIG. 10 is another perspective view thereof;

FIG. 11 is a perspective view of the massage gun where the massage gun is in a first configuration of use;

FIG. 12 is a perspective view of the massage gun where the massage gun is in a second configuration of use;

FIG. 13 is a perspective view of the massage gun where the massage gun is in a third configuration of use; and,

FIG. 14 is a perspective view of the massage gun where the massage gun is in a fourth configuration of use.

The dashed broken lines in the drawings depict portions of the massage gun that form no part of the claimed design. The dot-dash broken lines in the drawings depict environmental structure only and form no part of the claimed design.

1 Claim, 14 Drawing Sheets
